UNITED STATES PATENT OFFICE.

THOMAS S. HOMANS, OF HEMPSTEAD, NEW YORK, ASSIGNOR TO INTERNATIONAL
TYPESETTING MACHINE COMPANY, OF NEW YORK, N. Y., A CORPORATION OF
NEW YORK.

VISE-AUTOMATIC.

1,139,420.

Specification of Letters Patent. Patented May 11, 1915.

Application filed May 23, 1913. Serial No. 769,537.

To all whom it may concern:

Be it known that I, THOMAS S. HOMANS, a citizen of the United States, residing at Hempstead, in the county of Nassau and State of New York, have invented new and useful Improvements in Vise-Automatics, of which the following is a specification.

This invention relates to improvements in line composing and line casting machines, 10 and more especially to those of the linotype class wherein each line of matrices is presented to the mold by an elevator and the mold is moved up to the line of matrices preparatory to each cast.

15 The primary object of the invention is to provide improved means for automatically interrupting the operation of the machine should a line of matrices be improperly presented to the mold, thereby avoiding damage to the matrices or to any part of the machine.

20 To this end, the invention consists in certain improvements, and combinations and arrangements of parts, all as will be herein- 25 after more fully described, the novel features being pointed out particularly in the claims at the end of the specification.

In the accompanying drawings:—Figure 1 is an elevation of a portion of a machine 30 of the linotype class as viewed from the left-hand side and embodying the present invention; Fig. 2 is a front elevation of the parts shown in Fig. 1; Fig. 3 is a detail perspective view of a portion of the stop or 35 safety device; Fig. 4 is a top plan view showing the vise frame and elevator in horizontal section, and having the present invention applied thereto and shown in position to permit operation of the machine; Fig. 5 is a view similar to Fig. 4 but showing the device in a position to interrupt and prevent operation of the machine.

Similar parts are designated by the same reference characters in the several views.

45 In the accompanying drawings one example of the invention is shown in connection with a machine of the well known linotype class as described and illustrated fully in the patent to O. Mergenthaler, No. 50 436,532 granted September 16, 1890.

In the present instance 1 designates the disk or gear wheel which carries one or more molds 2.

55 3 designates the elevator slide forming part of what is generally known as the first

elevator, this elevator slide having an overhanging head at the top which carries jaws 4 which receive each line of matrices M between them, and when the elevator is lowered the line of matrices held by the elevator jaws is lowered to the proper level to be engaged by the mold 2. The elevator is guided to operate vertically on the vise frame 5, the latter having a cap 6 at the top which also guides the elevator as well as the vise jaws which clamp the line of matrices in an endwise direction, all as will be well understood by those skilled in the art. The mold disk or wheel 1 is revolvably supported by a bearing 7, this bearing being carried by a horizontally movable slide 8, and the slide 8 is provided with means for reciprocating it and consequently the mold disk or wheel 1 horizontally to move the mold 2 into engagement with the line of matrices supported by the elevator, preparatory to the casting of a slug, and after the cast has been made, the slide, together with the mold disk or wheel, is retracted or moved rearwardly away from the mold, whereupon the elevator may ascend to carry the line of matrices to the distributing mechanism and the mold disk or wheel may be rotated in the usual way to bring the mold containing the cast slug to the ejecting position.

A vertical screw 9 is fitted in the vise frame 5 and constitutes an adjustable stop, the upper end of which is arranged to be engaged by the under side of a slide 10, the latter being fitted in a horizontal guideway 11 formed in the elevator slide 3. This slide 10 has a handle 12 whereby it may be shifted laterally at will, a guide-pin 13 being provided to retain the slide in position and the under side of the slide is formed with a recess or notch 14, shifting of the slide into the right-hand position as shown in the drawings bringing the unnotched portion of the slide into position to engage the top of the screw 9 and shifting of the slide toward the left bringing the notch or recess 14 of the slide into a position to receive the upper end of the screw 9. This slide has a bar 15 extending downwardly therefrom and it is provided at its upper left-hand corner with a notch or cut-out portion which forms a surface 16 which is stepped a predetermined distance below the top surface 17 of the slide for a purpose that will hereinafter appear.

The mold slide 8 carries a guide 18, the latter having flanges to coöperate with the front and rear faces of the mold disk or wheel, and a rigid arm 19 is fixed to said 5 guide and projects into a position to push forwardly the left-hand end of a bar 20 when the mold disk or wheel is shifted forwardly into the casting position. The bar 20 rests between lugs 21 on the vise frame 5, 10 the upper lug 21 at the left-hand side being notched to receive a guide-pin 22 on the bar 20, and the upper lug 21 at the right-hand side of the vise frame having a retaining projection 23 to coöperate with a pin 24 on 15 the bar. A tension spring 25 operates to retain the left-hand end of the bar 20 in engagement with the arm 19. The opposite or right-hand end of the bar 20 extends into a position where it will engage the 20 roller 26 carried by a lever 27. This lever 27 is adapted to coöperate with the starting lever 28, the latter being pivoted at 29 and provided with an arm 30 which is pivotally connected to a link 31, the links 30 and 31 25 constituting a toggle and the link 31 being connected to the bar 32 which, when the toggle links are straightened, throws the main clutch of the machine out of operation and thereby stops the machine. The 30 starting handle and toggle operate substantially as disclosed in the Mergenthaler patent above referred to, and in the machines at present in use, to disengage the main driving clutch and interrupt the operation 35 of the machine when the toggle is straightened as shown in Fig. 5, the clutch being engaged and the machine in running condition when the starting handle is in the position shown in Fig. 4. The lever 27 when 40 pushed into the position shown in Fig. 5 by the bar 20 will shift the starting handle into stopping position and will engage behind a lug 33 of the link 30 and thereby stop the machine and prevent further operation thereof.

A lug 34 projects forwardly from the forward side of the bar 20, this lug serving as a fulcrum when it abuts against the slide 10 whereby the forward motion of the mold 50 slide will cause the arm 19 to push forwardly against the left-hand end of the bar 20 and thereby cause the bar 20 to rock about the lug 34 as a fulcrum, moving the right-hand end of the bar 20 rearwardly 55 and into stopping position, as shown in Fig. 5.

In the construction shown in the present instance, the machine is capable of handling matrices bearing characters arranged at two 60 different levels thereon, each mold having upper and lower ledges 35 and 36 to coöperate with the lower rear lugs on the matrices. In using the lower characters on the matrices, the slide 10 occupies the right- 65 hand position, the lower unnotched face of

the slide then coming against the stop screw 9, and in using the upper characters on the matrices, the slide 10 is shifted toward the left and the notched portion 14 in the slide will then receive the stop screw 9 and the 70 elevator is thereby permitted to descend to a lower point than in the previous instance. When the slide 10 occupies the right-hand position, (as it does when the lower characters on the matrices are used) the lug 34 75 on the bar 20 will just clear the stepped surface 16 on the slide 10 when this bar 20 is pushed forward by the corresponding movement of the arm 19 which occurs when the mold is moved up to the line of matrices 80 prior to the cast. When the slide 10 is moved toward the left, (as when the upper characters on the matrices are being used) the lug 34 on the bar 20 will then just clear the top surface 17 on the slide 10 when the mold is moved up to the line of matrices, and in these two cases, when the matrices are properly presented to the mold, the bar 20, 85 will not rock so as to move the starting handle into stopping position for the reason that the lug 34 does not bear on a fulcrum. If, however, the elevator does not descend to the proper point so as to bring the line of matrices correctly between the jaws of the vise, then the lug 34 will bear 90 against the rear side of the slide 10 or the downward extension 15 thereon, and the bar 20 will then rock in the manner shown in Fig. 5, throwing the clutch into disengaged condition and interrupting the operation of the machine. After the cast has 95 been made, the mold slide recedes from the line of matrices and the elevator rises to carry the line of matrices to the distributing mechanism.

In machines of this class, the mold slide is moved forward during the time the elevator is raised, for the purpose of ejecting the slug from the mold. The automatic stop which insures correct presentation of 100 the matrices to the mold, as constructed in accordance with the present invention, will not interfere with this advancing movement of the mold wheel during the slug-ejecting operation, as the slide 10 and its extension 15 are then clear of the bar 20 and its fulcrum lug 34, and the operation of the machine therefore, will not be interrupted. The present invention avoids the necessity 105 of using special devices to prevent stopping of the machine during this ejecting period, the stopping device of the present invention being controlled positively according to the position occupied by the elevator and independently of the position of any intermediate parts. Also, the stop device of the present invention is inoperative when the elevator is raised to its upper position, as well as when the elevator is lowered to its 110 proper limit, and it provides a very simple 115 120 125 130 135

means for adapting it to the use of matrices bearing characters at different levels thereon.

The present invention is an improvement 5 on the safety device of the Mergenthaler patent above mentioned, as in that patent the stopping of the machine is not dependent positively on the position of the elevator as the elevator in that construction 10 must push down a vertically movable rod which is held up by a spring, and it frequently occurs that the rod remains down after operation of the machine due to binding or friction in the bearings, or for other 15 reasons, and hence the subsequent operations of the machine are not controlled by the safety device.

I claim as my invention:—

1. In a machine of the linotype class, the 20 combination with the first elevator for lowering a line of matrices to the casting level, the casting mold, the slide for carrying the mold against the line of matrices, and stopping means for the machine, such means being 25 actuated during the forward movement of the mold and governed solely according to the position occupied by said elevator whereby operation of the machine will be interrupted should the elevator fail to properly 30 sent the matrices properly to the mold.

2. In a machine of the linotype class, the 35 combination with the mold, the slide carrying it, and the first elevator, of stopping means for the machine embodying a member actuated by the forward movement of the mold-carrying slide, and a part in the first elevator adapted to form an operative connection for said member, said part being 40 inoperative relatively to said member when the first elevator is lowered to a position to properly present matrices to the mold.

3. In a machine of the linotype class, the combination with the mold, the mold-car-

rying slide, and the first elevator, of stopping means for the machine embodying a 45 lever arranged to be acted on by said mold slide during its forward movement, and a part on the elevator adapted to coöperate with said lever as a fulcrum, the stopping means being inoperative when said part on 50 the elevator is above or below said lever.

4. In a machine of the linotype class, the combination with the mold, the mold-carrying slide, and the first elevator for presenting a line of matrices to the mold, of stopping 55 means for the machine embodying a member arranged to be actuated by the mold slide as the latter brings the mold against the line of matrices, and a part on the elevator arranged to form an operative 60 connection for said member when the elevator fails to bring the matrices to the proper casting level, said part on the elevator being adjustable to provide for the use of the upper or lower characters of 65 plural-character matrices.

5. In a machine of the linotype class, in combination with matrices having a plurality of characters, the first elevator for bringing a line of matrices down to casting 70 position, and a stop block having two sets of steps, each corresponding to the different character levels on the matrices, one set being adapted to stop the downward travel of the elevator at the different levels as desired, and the other set adapted to control the stopping of the machine in event of the elevator not reaching the stop of its downward travel.

In testimony whereof I have hereunto set 80 my hand in presence of two subscribing witnesses.

THOMAS S. HOMANS.
